(57) **CLAIM**

The ornamental design for a lanyard safety breakaway buckle, as shown and described herein.

DESCRIPTION

FIG. 1 is a top, left and front perspective view of a lanyard safety breakaway buckle embodying my new design; FIG. 2 is a front elevational view thereof, the rear elevational view being a mirror image thereof;

FIG. 3 is a right elevational view thereof, the left elevational view being a mirror image thereof; and,

FIG. 4 is a top plan view thereof, the bottom plan view being a mirror image thereof.

The broken lines in FIG. 1 illustrate portions of the lanyard safety breakaway buckle that form no part of the claimed design.
